UNITED STATES PATENT OFFICE.

RICHARD PHELAN, OF OAKLAND, AND FREDERICK BENDIX, OF SAN FRANCISCO,
CALIFORNIA.

BERTH.

1,350,081.

Specification of Letters Patent. Patented Aug. 17, 1920.

Application filed January 23, 1920. Serial No. 354,243.

To all whom it may concern:

Be it known that we, RICHARD PHELAN and FREDERICK BENDIX, citizens of the United States, residing at Oakland, in the county of Alameda, and in the city and county of San Francisco, respectively, in the State of California, have jointly invented a new and useful Improvement in Berths, of which the following is a specification.

10 Our invention relates to improvements in steamer berths and the like wherein an upper and lower berth, operate in conjunction with improved means for pivotally and resiliently suspending said berths between 15 the walls of a ship's compartment to prevent the transmission of the lateral movement and vibration of said ship to said berths.

The primary object of our invention is to 20 provide a new and improved berth for steamers and the like.

A further object of the invention is to provide an improved berth suspended pivotally and resiliently to prevent the transmission of the vibration and lateral rolling 25 of the ship to said berths.

A still further object of the present invention is to provide improved means for normally and automatically maintaining said 30 berths in a horizontal plane.

It is also an object of the present invention to provide upper and lower berths of a pendulous nature and adapted for movement within a limited space, relatively to 35 the ship's compartments within which they are pivotally and resiliently suspended.

We accomplish these and other objects by means of the improved device disclosed in the drawings forming a part of the present specification wherein like characters of reference are used to designate similar parts throughout the said specification and drawings, and in which—

Figure 1 is a vertical, broken sectional view of a portion of a ship's compartment disclosing the manner of pivotally and resiliently suspending the berths; and

Fig. 2 is a broken end elevation of the berths.

50 Referring to the drawings the numeral 1 is used to designate the opposite walls of a ship's compartment, each wall having a vertically disposed slot 2 therein said slots being arranged opposite each other.

55 Alined above each slot 2 and mounted

upon the walls 1 is a bracket 3 within which brackets 3 are slidably mounted for vertical movement only the pins 4 having enlarged heads 6 resting upon suitable springs 7.

An upper berth 8 is provided with brackets 9 pivotally engaging the lower ends of the pins 4, said pivotal points being arranged above and coaxial with the longitudinal center of the said upper berth 8.

A lower berth 11 is provided with 65 brackets 12 on each end thereof arranged to pivotally and slidably engage the slots 2 of the walls 1.

Connecting rods 14 pivotally connect the corners of the upper and lower berths 8 70 and 11 respectively whereby parallel positions may be assumed by said berths when moved on their pivotal points.

A pendulum weight 16 is secured to the lower berth 11 by means of which, and the 75 connecting rods 14, both berths 8 and 11 may be normally and automatically retained in a horizontal plane during the rolling of the ship, within a comparatively limited space. That is, the pivotal points of each 80 berth being mounted for vertical as well as pivotal movement, it is evident that the lower berth, instead of swinging from the pivotal point of the upper berth, will swing from its own independent pivotal point as 85 represented by the brackets 12 and slots 2, the plane of the upper berth 8 being retained parallel to the lower berth 11 by means of the connecting rods 14, which novel arrangement and feature will shorten 90 the radius of the arc through which the lower berth 8 swings.

Upon the lower surface of one end of the lower berth 11 we have mounted a sector 17 provided with notches or recesses 18 95 engageable by a toothed locking-weight 20 slidably mounted for vertical movement within a plate 22 secured to the adjacent wall 1 of the compartment.

A cord 23 is secured to the locking weight 100 20 and passes over a suitable pulley 24 directly above said lock-weight 20 and thence over a second pulley 26 and to an arm 27 upon a vertically disposed rod 28 rotatably mounted upon the adjacent wall 1 of the 105 compartment. The rod 28 is provided with operating handles 29 conveniently located adjacent the head of each berth so that by means of said handles 29 rod 28 may be partially rotated to move the arm 110

27 and thereby pull the cord 23 and raise the locking-weight 20 to disengage the same from the teeth 18 of the sector 17 thereby permitting movement of the berths 8 and 11 relatively to the ship.

11 relatively to the ship. The locking-weight 20 may be locked in disengaging position by moving the arm 27 past a center line drawn between the pulley 26 and the center of said rod 28 whereby 10 tension of the cord occasioned by said weight will tend to move the arm 27 against the wall 1 and thereby prevent lowering of the weight 20.

From the foregoing it is obvious that the berths, being resiliently suspended will be free of vibration as such vibration of the ship will be absorbed by the springs 7. It is also obvious that the pendulum weight 16 will tend to retain the berths 8 and 11 20 in a horizontal plane and in parallel position to each other through the medium of the connecting rods 14.

Having thus described our invention what we claim as new and desire to secure by Letters Patent is—

20 1. A non-vibrating berth comprising a berth having brackets at each end thereof whereby said berth may be suspended; and means for pivotally and resiliently engag-
30 ing the brackets to prevent transmission of vibration and lateral movement of a ship within which the berth may be suspended, to said berth, and means slidably engaging the berth for locking said berth against lateral movement and permitting vertical movement relatively to said ship.

movement relatively to said ship.

2. A non-vibrating berth for ships and the like comprising opposite compartment walls on said ship; brackets mounted opposite each other on said walls; pins mounted for vertical movement within said brackets; means for resiliently resisting said vertical movement; a berth pivotally connected to the pins whereby transmission of vibration of said berth may be prevented; a second berth arranged below the first berth; and suitable connecting rods connected to each corner of both berths whereby said second mentioned berth may be pivotally suspended from said first mentioned berth;

brackets secured to each end of the second mentioned berth, and means secured to the compartment walls for slidably engaging said brackets for vertical movement whereby movement of the first mentioned berth 55 may be duplicated and transmitted to said second mentioned berth.

second mentioned berth.

3. A non-vibrating berth for ships and the like comprising an upper and lower berth; connecting rods connecting the berths at their corners; pivotal brackets mounted upon each end of each berth; means for slidably engaging the brackets of the lower berth; and resilient means for pivotally engaging the brackets of the upper berth; whereby transmission of vibration of the ship to both berths may be prevented. 65 60

4. The combination with a ship of opposite compartment walls having vertically disposed oppositely arranged slots therein; a pair of pins alined with and mounted for vertical movement above the slot; means for resiliently supporting the pins; an upper and a lower berth mounted between the pins and slots respectively; connecting rods pivotally connecting the corners of the berths; brackets on the ends of the upper berth pivotally engaging the pins; and brackets on the ends of the lower berth pivotally and slidably engaging the slots in the compartment walls whereby both berths may be resiliently and pivotally suspended to prevent the transmission of lateral movement and vibration of said ship to said berths. 70 75 80

5. The combination with a ship and compartment therein of a pair of berths arranged one above the other and having independent pivotal points arranged above the longitudinal center of each berth; means for pivotally connecting the corners of both berths; means for slidably and pivotally engaging the pivotal points of the lower berth; and resilient means pivotally connected to the pivotal points of the upper berth whereby transmission of vibration and rolling of said ship to said berths may be prevented. 95

In witness whereof we hereunto set our signatures.

RICHARD PHELAN.
FREDERICK BENDIX.
